COUNTER TRANSFER AND CLEARING
MECHANISM

Eugene M. La Boiteaux, Washington, D. C.

Application December 2, 1935, Serial No. 52,604

17 Claims. (Cl. 235—133)

The invention relates to machines for mechanically adding simultaneously amounts comprising a plurality of digits in which the method of carrying or transferring the increment from a lower to the next higher denomination is usually accomplished by a successive or step-by-step method immediately following the accumulative interval and forming a part of a complete cycle as determined by controlling devices. In counters or registers of large field capacity, this interval is necessarily short and, where speed may be demanded, results are liable to error. The method herein presented accomplishes this result in a more direct manner by merging the carrying or transferring of the increments from lower denominations to higher denominations within or practically simultaneously with the accumulative interval with a consequent reduction in the number of working parts.

10 A further object of the invention is to provide a transfer unit for carrying or transferring the increment from a lower to the next higher denomination of an extremely simple and compact character adapted to be mounted directly on the continuously rotating shaft between frictionally driven escapement type counter wheels and capable of automatic operation during the accumulative interval as the necessity for increment transfer from any of the number wheels to 15 a number wheel of the next higher denomination occurs, thereby entirely eliminating the heretofore successive or step-by-step transfer interval occurring immediately following the accumulative interval, whereby greater accuracy in 20 the operation of the counter transfer mechanism and increased speed of the same and the indexing or other machine with which such counter transfer mechanism may be associated are obtained.

25 As a method for clearing or zero alignment of this type of counter is one of considerable importance, it is also an object of the invention to enable this operation to be accomplished in a simple, effective and accurate manner and by 30 the use of a minimum number of parts.

With these and other objects in view, the invention consists in the construction and novel combination and arrangement of parts herein-after fully described, illustrated in the accompanying drawings and pointed out in the claims hereto appended, it being understood that various changes in the form, proportions and minor details of construction may be resorted to without departing from the spirit or sacrificing any 35 of the advantages of the invention.

In the drawings:

Figure 1 is a front elevation of counter transfer and clearing mechanism constructed in accordance with this invention.

Figure 2 is a vertical sectional view on the line 5 2—2 of Figure 1 showing the counter transfer and the clearing mechanism in side elevation.

Figure 3 is an enlarged side elevation of a type or number wheel and transfer unit partly in section, the carry arm being also shown. 10

Figure 4 is a vertical longitudinal sectional view of the counter transfer mechanism.

Figure 5 is a vertical sectional view on the line 5—5 of Figure 4.

Figure 6 is a sectional view of the type or number wheel illustrating the arrangement of the floating driving dog and the spring for urging the driving dog tangentially and radially. 15

Figure 7 is a similar view illustrating the arrangement of the friction drive of the type or 20 number wheel.

Figure 8 is a detail side elevation illustrating the construction of the clearing mechanism.

Figure 9 is a vertical sectional view of the ratchet disk of the transfer unit. 25

Figure 10 is an elevation of the ratchet disk showing one side of the same.

Figure 11 is a similar view showing the other side of the ratchet disk of the transfer unit.

Figure 12 is a detail sectional view illustrating 30 the toothed sleeve of the transfer unit.

Figure 13 is a detail side elevation of the toothed sleeve.

Figure 14 is a detail sectional view of the number or type wheel. 35

Figure 15 is a detail view of one of the fiber disks of the friction drive.

Figure 16 is a similar view of one of the metal disks of the friction drive.

In the accompanying drawings in which is illustrated one embodiment of the invention, I designate a frictional driven number or type wheel consisting of a disk having a central opening 2 and arranged on a continuously rotating shaft 3 and frictionally driven by the said shaft by 40 means of interleaved friction disks 4 and 5 alternately arranged as clearly illustrated in Figure 4 of the drawings and keyed respectively to the number or type wheel 1 and the continuously rotating shaft 3. The friction disk assembly is 45 of the ordinary wellknown construction, the friction disk 4 being designed to be constructed of fiber or other suitable material and the friction disk 5 of metal. The fiber disks are preferably 50 provided at the periphery with projecting lugs 55

6 arranged preferably 120° apart and engaging keyways 7 formed in the wall of a recess 8 of the number or type wheel 1. The friction disks 5 are each provided with a lug 9 which engages a keyway 10 of the continuously rotating splined shaft 3. The friction disks 4 and 5 which have central openings 11 and 12 for the passage of the shaft 3 are maintained in frictional engagement by a coiled conical spring 13 which is compressed into a flat coil as clearly illustrated in Figures 4 and 7 of the drawings and which maintains the friction disks in contact with one another so that when the number wheel is free to rotate, it will be rotated by the continuously rotating shaft 3.

15 The friction drive also permits the type or number wheel to be restrained and normally held against rotary movement by a locking pawl 14 which is arranged to engage outer ratchet teeth 15 of a ratchet ring 16. The ratchet ring 16, which constitutes an escapement wheel for the number or type wheel instead of forming an integral part of the type or number wheel, as heretofore, is in the form of a ring free to rotate 20 in one direction and mounted on an annular boss 17 extending from the side of the number or type wheel opposite that at which the friction disks are arranged and retained thereon by a plate 18 consisting of a ring secured to the outer face 25 of the annular boss 17 by suitable fastening devices 19.

25 The ratchet ring is provided at its inner periphery with shallow internal teeth 20 corresponding with the external teeth 15 and arranged to be engaged by a floating driving dog 21 which causes the ratchet ring to rotate with the number or type wheel. The floating driving dog, which consists of a curved body portion, operates within a recess 22 in the annular boss of the number or type wheel, and it is mounted on a fixed stud 23 carried by said type or number wheel and extending through a slightly enlarged approximately elliptical opening 24 in the floating driving dog 21. The enlarged opening 24 permits pivotal movement of the dog and also a limited longitudinal movement of the same.

30 The floating driving dog 21 is provided at one end with an outwardly or radially projecting tooth 25 which engages an internal tooth of the ratchet ring 16, and it is provided at its other end with a substantially arcuate arm 26 located within the recess defined by the annular boss 17 and projecting beyond one end of the recess 22. The arm 26 is normally arranged approximately concentric with the continuously rotating shaft 3 and the floating driving dog is urged longitudinally in a direction substantially tangentially or circumferentially with relation to the ratchet ring and radially by a curved approximately circular spring 27 suitably secured at one end 28 to the number or type wheel and connected at its other end 29 with the body portion of the floating driving dog at the rear end thereof. The spring 27, which may have its end 29 seated in a socket 30 of the floating driving dog, may be otherwise connected therewith, and it is adapted to maintain the tooth 25 in engagement with the ratchet ring and it is also capable, when the arm 26 is actuated by transfer mechanism hereinafter described and the tooth 25 withdrawn from engagement with the ratchet wheel, of moving the floating driving dog tangentially a sufficient distance to carry the tooth 25 a short distance beyond the previously engaged internal tooth 20 of the 35 ratchet ring 16. The operation insures the ro-

tation of the number or type wheel one division or the distance of one tooth, as the friction drive will rotate the type or number wheel until the floating driving dog engages the next internal tooth 20, provided the number wheel is restrained by the locking pawl 14 at the time the floating driving dog is operated by the said transfer mechanism.

35 Should, however, the driving dog be operated while the number or type wheel is rotating and therefore unrestrained by the locking pawl 14, the floating driving dog will be carried to a point beyond the previously engaging internal ratchet tooth 20 and after the completion of the said rotary movement of the number or type wheel due to a control card of an indexing machine having withdrawn the locking pawl 14 from engagement with the ratchet ring, the floating driving dog will permit the number or type wheel to rotate one division or the distance of one tooth in excess of that effected by the control card after the locking pawl 14 has reengaged and restrained the ratchet ring. When the locking pawl 14 has reengaged the ratchet ring 16 the friction drive will continue the rotation of the number or type wheel to which the floating dog 21 is pivoted until the floating dog 21 engages the next internal tooth or shoulder 20 of the ratchet ring 16. This obviates a second operation of the locking pawl 14 which has heretofore been necessary to accomplish this result.

40 The transfer unit comprises a toothed central sleeve 31 arranged on the continuously rotating shaft and provided with a key lug 32 which fits in the keyway 10 of the shaft 3, whereby the sleeve 31 is fixed to and rotates with the shaft 3. The central sleeve 31 is provided at its periphery with approximately triangular teeth 33 having oppositely inclined faces and forming tapering recesses 34 which receive an annular series of 45 balls 35 mounted in a slotted ball-carrier boss 36 of a ratchet disk 37. The ratchet disk 37 is provided with a central opening 38, and it is arranged on an annular shoulder 39 of the toothed sleeve 31 and is held on the toothed sleeve 31 by a retaining plate 40, which fits within an annular recess 41 in the ratchet ring and is arranged in flush relation with the same. The retaining plate is pressed on the toothed sleeve and secured in place by staking the end of the sleeve 50 but any other suitable means may be employed for securing the retaining plate on the toothed sleeve.

55 The annular boss 36 is provided with radial openings 44 which are cylindrical to permit radial movement of the balls 35. The balls are directed radially by an endless helical spring 46 arranged in the form of a ring and encircling the annular series of radially movable balls and located adjacent the arm 26 of the floating driving dog 21, whereby when the ratchet disk which normally rotates with the toothed sleeve is restrained by the carry arm 43, the balls 35 will be moved radially outwardly by the inclined faces of the teeth 33 of the sleeve 31 and will expand the endless helically coiled spring 46 and cause the same to engage the arm 26 of the floating driving dog 21 and withdraw the tooth 25 thereof from engagement with an internal tooth of the ratchet ring to permit the number or type wheel to rotate one division, transferring an increment from one number wheel to another number wheel of the next higher denomination. The balls 35 constitute radially movable elements, and the radially movable elements may be varied, and instead 65

of employing balls, radially movable elements of any other form may be employed. Also, instead of employing a continuously coiled helical spring, any equivalent resilient means may be provided 5 for directing the balls radially and for expanding circumferentially to operate the floating driving dog.

The splined shaft is common to all the number or type wheels 1, and each type or number 10 wheel is provided at the side opposite that having the bars 17 with a cam disk 47 secured to the number or type wheel by suitable fastening devices 48 and retaining the friction drive assembly within the recess 8 of the number or type wheel. 15 The cam disk is located at one side of the number or type wheel 1, and the plate or ring 18 is located at the opposite side thereof, and separate fastening devices are illustrated in the drawings for securing these parts in place, but they may be 20 secured to the type or number wheel 1 in any other suitable manner. Also a carry arm 43 is associated with each number wheel and is maintained normally in engagement with the periphery of the cam disk by a spring 49. The carry 25 arms 43 are mounted on a fixed shaft 50 for independent movement and each rides on the periphery of the cam disk and is provided with a laterally extending tooth 51 arranged to engage the ratchet disk 37 for momentarily restraining 30 the ratchet disk against rotation for causing a circumferential expansion of the annular resilient member 46 to actuate the floating driving dog and withdraw its tooth 25 from engagement with an internal tooth 20 of the ratchet ring 16. The 35 cam disk 47 is provided in its periphery with a recess 52 adapted to permit the carry arm to drop into it and allow the tooth 51 to engage the ratchet disk 37. The number or type wheel 1 and its cam disk 47 rotate in the direction of the arrow in Figure 2 of the drawings, and the recess 52 is provided at its rear end with an inclined or 40 beveled wall 53 which is adapted, through the rotary movement of the cam disk 47, to lift the carry arm 43 out of engagement with the ratchet disk 37.

After the carry arm 43 has been lifted out of engagement with the ratchet disk 37, it is retained by the periphery of the cam disk 47 out of engagement with the ratchet disk 37 until the 45 number wheel has again made a complete rotation and the recess 52 is again brought into position to permit the carry arm to drop into engagement with the ratchet disk 37. It will thus be seen that the transfer mechanism will be automatically operated once during each rotation of the number or type wheel for the transfer of an increment to the number wheel of the next higher denomination. Each carry arm is provided with a lug or projection 54 arranged at an angle to the carry 50 arm and the spring 49 is connected at one end to the lug or projection 54 and at its other end to a fixed portion on the frame for maintaining the carry arm in engagement with the cam disk of the number or type wheel. A laterally projecting tooth 51 of the carry arm is arranged to coat with the transfer mechanism of the adjacent number or type wheel, so that when the carry arm of one number or type wheel is operated by the cam disk of such type wheel, the ratchet disk 55 of the number or type wheel of the next higher denomination will be momentarily arrested to effect the automatic transfer of an increment from a number or type wheel of the next lower denomination to the number or type of the next 60 higher denomination. The arresting of the

ratchet disk 37 by the tooth 51 of the carry arm 43 will cause an expansion of the helically coiled spring 46 and withdraw the tooth 25 of the driving dog 21 from engagement with an internal tooth 20 of the ratchet ring to permit the number 5 or type wheel to rotate one division and transfer an increment from one number wheel to another as heretofore explained. This is due to the fact that the floating driving dog 21 has been disengaged from one of the internal teeth 21 of the 10 ratchet ring and has, through its circumferential movement, advanced beyond such tooth to a position which, upon rotation of the ratchet ring, will enable it to engage the next internal tooth 21 of said ratchet ring. If at the moment of the disengagement of the floating driving dog 21 the ratchet ring 16 is under restraint of movement by the locking pawl 14, the number or type wheel will immediately rotate one division or register an increment of one. Should, however, this same 15 number or type wheel be rotating or in the act of accumulating an increment as determined and controlled by any indexing device by cessation of interference of said locking pawl 14, the floating driving dog 21, although rotating with the number or type wheel and with the ratchet ring 16, will be disengaged from the internal tooth 20 of the ratchet ring at the carry position of the number wheel of the next lower denomination and when said locking pawl 14 again arrests the rotation of the ratchet ring 16, said number or type wheel will continue its rotation an additional one division and thus accumulate the increment, one, transferred from said number or type wheel of the next lower denomination as heretofore explained. 20

The number or type wheels 1 are provided at their peripheries with raised type or numbers 55, ranging from nought to nine in the ordinary manner and adapted to have an impression taken from the result by any suitable printing means. The recesses or cutaway portions 52 of the cam disks are associated with the ciphers or noughts of the printing type or numbers so that the increment, one, is transferred from one type or 25 number wheel to the type or number wheel of the next higher denomination, while the type or number wheel of the lower denomination is rotating from nine to nought, but the printing line may be arranged at any convenient point around 30 the periphery of the type or number wheels. 35

Clearing or zero alignments at the completion of integrating operations is accomplished by means of resilient detents 56 adapted to engage the carry arms 43 and maintain the same in the 40 recesses or cutaway portions 52 of the cam disks for holding the type or number wheels against rotation until a zero alignment of the type or number wheels is effected. The resilient detents 56 are secured to and extend downwardly beyond 45 depending arms 57 of a cam control rock shaft 58 as clearly illustrated in Figures 1 and 2 of the drawings. The detent 56 is normally slightly separated from and out of engagement with a shoulder 50 of the carry arm 43 by control through a one- 55 rotation cam 61. The cam also actuates a sliding collar 62 by means of an angle shifting lever 63 having a forked arm 64 and a cam actuated arm 65. The forked arm 64 is provided with pins or studs 66 having antifriction sleeves 67 and extending into a peripheral cam groove 68 of the one-rotation cam 61. The cam 61 when tripped makes one complete rotation and then stops at the starting position. The rotation of a one-rotation cam is determined by the driving mechanism 60 65 70 75

and its cessation after the cam has made one revolution. As this is well known in the arts, further illustration or explanation thereof is believed unnecessary. The angle shifting lever 63 is fulcrumed by a suitable pivot 69 on a fixed portion of the frame 70 of the machine, and the cam groove 68 of the cam 61 has a laterally extending cam portion 72 which normally maintains the sliding collar 62 out of engagement with a laterally projecting beveled portion 73 of the floating driving dog 21 of the units denomination type or number wheel. The beveled laterally extending portion 73 is engaged by a beveled peripheral portion 74 of the sliding collar for operating the floating driving dog 21 of the units denomination type or number wheel.

The rock shaft 59 is provided with a cam controlled arm 75 located at one side of the cam 61 and provided with a laterally projecting stud 76 having an antifriction sleeve 77 operating in a cam groove 78 formed in the inner side face of the cam 61 and having an inwardly directed offset or cam portion 79 which normally maintains the resilient detents 56 out of engagement with the carry arms. The clearing or resetting to zero of all type wheels is effected by a single rotation of the cam 61 which may be operated by any suitable means either manually or automatically. The rotation of the cam 61 from the position illustrated in Figure 2 of the drawings moves the cam controlled arm 75 of the rock shaft 59 outwardly and carries the resilient detents into engagement with the carry arms and is adapted to hold the carry arms in the recesses 52 of the cam disks against the action of the friction drive of the number or type wheels by engagement with the rise or beveled end wall 53 of the said recess 52.

The carry arms are each provided adjacent the shoulders 60 with a recess 80 adapted to be engaged by the coacting detent 56 for maintaining the carry arm in engagement with the said recess 52 of the cam disk 47. If the carry arm 43 actuated by the spring 49 should be riding on the periphery of the cam disk 47, the resilient detent 56 will be flexed by contact with the shoulder 60 and, upon further rotation of the cam disk 47, the carry arm will move downwardly into the cam area or recess 52 of said cam disk 47, thereby permitting the resilient detent to assume a vertical position above and in engagement with the recess 80, thereby preventing further rotation of the type or number wheel by engaging or contacting with the beveled wall or rise 53 of the cam disk 47. Immediately preceding the flexing of the detent 56, by the rotation of the cam 61, the deflector collar 62 is shifted longitudinally of the shaft by the cam 72 to release the floating driving dog from the engaged internal tooth of the ratchet ring of the units denomination of the type or number wheel, thus permitting free rotation of said type or number wheel to zero position. The clearing action advances successively from the units denomination type or number wheel to the type or number wheels of higher denominations and the clearing action of the type or number wheels of higher denominations than said units denomination type or number wheel may be successive or simultaneous, according to the positions of the type or number wheels depending upon the prior rotation of the type or number wheels toward the zero aligning or clearing position.

The shaft 3 which rotates continuously in the same direction will in practice be connected by a

suitable gearing with the tabulating or other machine with which the counter transfer and gearing mechanism is used and it will rotate in synchronism with such machine. The stop pawls 14 which constitute latches for normally restraining or holding the counter members or units 1 against rotation with the continuously rotating shaft 3 are adapted to be operated by any suitable indexing or tabulating mechanism for individually releasing the counter members 1 for 10 simultaneously adding a plurality of digits.

As tabulating or indexing mechanism for recording or accumulating and recording the results of numbers represented by perforations in record cards commonly used in connection with systems of mechanical tabulation, is well known in the art illustration of such means for operating the stop pawls or latches 14 for releasing the counter members 1 individually for timed intervals, is deemed unnecessary. A preferred mechanism for 20 accomplishing this result is disclosed and claimed in an application filed by me August 7, 1935, Serial No. 35,217, but any other equivalent mechanism may of course be employed.

What is claimed is—

1. In mechanism of the class described, a continuous rotary shaft, a counter member carried by the shaft, an escapement wheel associated with the counter member, a driving dog mounted on the counter member and normally engaging the escapement wheel for causing the escapement wheel to rotate with the counter member, means for engaging the escapement wheel for normally holding the counter member against rotation with the shaft, and means actuated by the counter member of the next lower order at the completion of a cycle of its movement for operating the driving dog to release the counter member and permit a certain rotative movement thereof while the said holding means is engaged with the escapement wheel for transferring an increment to the counter member from a counter member of the next lower denomination.

2. In mechanism of the class described, a continuous rotating shaft, a counter member carried by the shaft, an escapement wheel associated with the counter member and mounted for relative rotative movement, a driving dog mounted on the counter member and normally engaging the escapement wheel for causing the escapement wheel to rotate with the counter member, a latch for engaging the escapement wheel for normally holding the counter member against rotation with the shaft and mechanism actuated by the counter member of the next lower order at the completion 55 of a cycle of its movement for operating the driving dog to release the counter member and permit a certain rotative movement thereof while the latch is in engagement with the escapement wheel for transferring an increment to the counter member from a counter member of the next lower denomination.

3. In mechanism of the class described, a continuous rotary shaft, a counter member carried by the shaft, an escapement wheel associated with the counter member and having internal and external teeth, a driving dog mounted on the counter member and arranged to engage the internal teeth of the escapement wheel for causing the same to rotate with the counter member, means for engaging the external teeth of the escapement wheel for normally holding the counter member against rotation with the shaft, and mechanism actuated by the counter member of the next lower order at the completion of a cycle 75

- 5 of its movement for operating the driving dog to release the counter member and permit a certain rotative movement thereof for transferring an increment to the counter member from a counter member of the next lower denomination

10 4. In mechanism of the class described, a continuous rotary shaft, a counter member carried by the shaft, a ratchet ring associated with the counter member and provided with internal teeth, a driving dog connected with the counter member and arranged to engage the internal teeth of the ratchet ring for causing the ratchet ring to rotate with the counter member, and mechanism actuated by the counter member of the next lower order upon completion of its cycle of movement and including radially movable means for operating the driving dog to release the counter member to permit a rotating movement thereof.

15 5. In mechanism of the class described, a continuous rotary shaft, a counter member carried by the shaft, a ratchet ring associated with the counter member and provided with internal teeth, a floating driving dog connected with the counter member and engaging the internal teeth of the ratchet ring for causing the latter to rotate with the counter member, said driving dog being movable radially and substantially tangentially with relation to the ratchet ring, mechanism including radially movable means actuated by the counter member of the next lower order upon completion of its cycle of movement for operating the driving dog to release the counter member to permit a rotative movement thereof, and resilient means for actuating the driving dog in its radial and tangential movements whereby a positive release of the counter member is effected for said rotating movement.

20 6. In mechanism of the class described, a continuous rotary shaft, a counter member carried by the shaft, a ratchet ring associated with the counter member and having internal teeth, a driving dog mounted on the counter member and arranged to engage the internal teeth for causing the ratchet ring to rotate with the counter member, and mechanism actuated by the counter member of the next lower order upon completion of its cycle of movement and including a sleeve rotating with the shaft and provided with teeth, radially movable elements normally located between the teeth of the sleeve and adapted to be moved outwardly by rotary movement of the sleeve, means for guiding the radially movable elements in their radial movement, and resilient means actuated by said elements radially for operating the driving dog to release the counter member and permit a rotative movement of the same.

25 7. In mechanism of the class described, a continuous rotary shaft, a counter member carried by the shaft, a ratchet ring associated with the counter member and having internal teeth, a driving dog mounted on the counter member and arranged to engage the internal teeth for causing the ratchet ring to rotate with the counter member, and mechanism actuated by the counter member of the next lower order upon completion of its cycle of movement and including a toothed sleeve rotating with the shaft, a ratchet disk normally rotating with the toothed sleeve, radially movable elements guided by the ratchet disk, resilient means maintaining the said elements in engagement with the toothed sleeve for causing the ratchet disk to rotate normally with the sleeve and means for hold-

30 ing the ratchet disk against rotation for causing the toothed sleeve to move the said elements outwardly and cause the resilient means to operate the driving dog and release the counter member for a rotative movement with the shaft for transferring an increment to the counter member from a counter member of the next lower order.

35 8. In mechanism of the class described, a continuous rotary shaft, a counter member carried by the shaft, a ratchet ring associated with the counter member and having internal teeth, a driving dog connected with the counter member and arranged to engage the internal teeth for causing the ratchet ring to rotate with the counter member, and mechanism actuated by the counter member of the next lower order upon completion of its cycle of movement and including a sleeve rotating with the shaft, a ratchet disk adjacent the said sleeve, resilient radially movable means carried by the ratchet disk and coacting with the said sleeve for causing the ratchet disk to rotate normally with the sleeve, the latter being provided with means for actuating the radially expansible means to operate the driving dog and release the counter member when the ratchet disk is held against rotary movement, and an arm provided with means for engaging and holding the ratchet disk against rotation.

40 9. In mechanism of the class described a continuous rotary shaft, a counter member carried by the shaft, a ratchet ring associated with the counter member and having internal teeth, a driving dog mounted on the counter member and arranged to engage the internal teeth for causing the ratchet ring to rotate with the counter member, and mechanism actuated by the counter member of the next lower order upon completion of a cycle of its movement and including a transfer unit mounted on the shaft and provided with a ratchet disk normally rotating with the shaft, said transfer unit having means associated with the ratchet disk for operating the driving dog to release the counter member and permit a rotative movement when the ratchet disk is arrested, an arm arranged to engage the ratchet disk and a cam normally maintaining the arm out of engagement with the ratchet disk and provided with means for releasing the arm to enable the same to engage the ratchet disk when a counter member has completed a rotative movement.

45 10. In mechanism of the class described, a continuous rotary shaft, a counter member carried upon the shaft, an escapement wheel associated with the counter member, a driving dog connected with the counter member and normally engaging the escapement wheel for causing the escapement wheel to rotate with the counter member and adapted to be moved out of such engagement to permit independent rotative movement of the counter member by said shaft, means for engaging the escapement wheel for normally holding the counter member against rotation with the shaft, and zero positioning mechanism including means for operating the driving dog to release the counter member and for holding the dog out of engagement with the escapement wheel until the counter member has reached a zero position.

50 11. In mechanism of the class described, a continuous rotary shaft, a counter member carried by the shaft, a ratchet ring associated with the counter member and having internal teeth,

a floating driving dog connected with the counter member and arranged to engage the internal teeth of the ratchet ring for causing the ratchet ring to rotate with the counter member, a transfer unit mounted on and normally rotating with the shaft and provided with a ratchet disk and having means for operating the driving dog to release the counter member and permit rotating movement thereof when the ratchet disk is arrested, a carry arm arranged to engage the ratchet disk, a cam for maintaining the carry arm out of engagement with the ratchet disk until a counter member of the next lower order has completed a cycle of rotating movement, and means for maintaining the carry arm in engagement with the ratchet disk to permit rotation of the counter member until the same has reached a zero position.

12. In mechanism of the class described, a continuous rotary shaft, a counter member carried by the shaft, a ratchet ring associated with the counter member, a floating driving dog connected with the counter member and engaging the ratchet ring for causing the same to rotate with the counter member, a transfer mechanism mounted on the shaft and including a ratchet disk mounted on and normally rotating with the shaft, means controlled by the ratchet disk and operated by the same to actuate the driving dog and release the counter member when the ratchet disk is arrested, a cam controlled carry arm arranged to engage the ratchet disk when a counter member of the next lower order has completed a cycle of rotating movement, and means for maintaining the carry arm in engagement with the ratchet disk to permit rotation of the counter member until the same has reached a zero position.

13. In mechanism of the class described, a continuous rotary shaft, a counter member carried by the shaft, a ratchet ring associated with the counter member, a floating driving dog connected with the counter member and engaging the ratchet ring for causing the same to rotate with the counter member, a transfer mechanism including a ratchet disk mounted on and normally rotating with the shaft, means controlled by the ratchet disk and operated by the same to actuate the driving dog and release the counter member when the ratchet disk is arrested, a cam controlled carry arm arranged to engage the ratchet disk when a counter member of the next lower denomination has completed a cycle of rotating movement, and zero positioning mechanism provided with means for maintaining the carry arm in engagement with the ratchet disk to permit rotation of the counter member until the same has reached a zero position.

14. In mechanism of the class described, a continuous rotary shaft, a counter member carried by the shaft, a ratchet ring associated with the counter member, a floating dog connected with the counter member and arranged to engage the ratchet ring for causing the ratchet ring to rotate with the counter member, a transfer mechanism including a ratchet disk mounted on and normally rotating with the shaft, means controlled by the ratchet disk for operating the driving dog to release the counter member when the ratchet disk is arrested, a cam controlled carry arm ar-

ranged to engage the ratchet disk when a counter member of the next lower order has completed a cycle of rotating movement, a rock shaft provided with a resilient detent arranged to engage the carry arm for maintaining the same in engagement with the ratchet disk until the counter member has reached a zero position, and a cam for controlling the operation of the rock shaft.

15. In mechanism of the class described, a continuous rotary shaft, two counter members of successive orders carried by the shaft, means carried by the shaft for rotating the counter members when the same are free to rotate, means normally holding the counter members against rotation with the shaft including a latch for each counter member, said latches being adapted to be operated to release the counter members to permit rotation thereof by said shaft, and means associated with the counter members and adapted to be actuated by the counter member of the lower denomination for operating at least the digit carrying portion of the counter member of the higher denomination for causing rotation thereof by said shaft without operating the latch and while the latch is in its holding position.

16. In mechanism of the class described, a continuous rotary shaft, two counter members of successive orders carried by the shaft, means carried by the shaft for rotating the counter members when the same are free to rotate, means normally holding the counter members against rotation with the shaft including a latch for each counter member, said latches being adapted to be operated to release the counter member to permit rotation thereof by said shaft, and means interposed between the counter members and adapted upon a complete rotation of the counter member of the lower denomination to operate at least the digit carrying portion of the counter member of the higher denomination to cause the same to be rotated by the shaft a certain degree substantially immediately upon such operation and independently of the releasing of the latch and while the latch is in its normal holding position.

17. In mechanism of the class described, a continuous rotary shaft, two counter members of successive orders carried by the shaft, means carried by the shaft for rotating the counter members when the same are free to rotate, means normally holding the counter members against rotation with the shaft including a latch for each counter member, said latches being adapted to be operated to release the counter members to permit rotation thereof by said shaft, and mechanism associated with the counter members and actuated by the counter member of the lower denomination upon the counter member of the lower denomination making a complete rotation for simultaneously causing operation of at least the digit carrying portion of the counter member of the higher denomination for causing rotation thereof a predetermined degree and thereby transfer an increment to the counter member of the higher denomination simultaneously and continuously with the adding of a plurality of digits.
